STREET PLATE FOR CRAWLER TYPE
TRACTOR SHOES

George W. O'Connor, Sacramento, Calif.

Application August 10, 1935, Serial No. 35,645

1 Claim. (Cl. 305—10)

This invention relates to the tractor art, and particularly to track construction of the crawler type tractor, the invention being specifically directed to street plates for the shoes of that type of tractor track.

In most localities there are laws which prohibit the running of the tractors on streets and highways unless smooth street plates are mounted over the shoes to prevent the grousers on the 10 shoes from cutting into and impairing the street or highway surface.

Heretofore these street plates have been commonly stamped or forged from relatively light weight material. Of course the wear on the 15 plates is quite rapid and these plates as previously commonly constructed would quite quickly wear thin. The bearing faces of the plates are unsupported and therefore when worn thin they tend to cup or cave inwardly leaving projecting edges around such cupped or caved portions, which edges will cut into the street or highway surface thus lessening the effectiveness of such plates.

It is the primary object of my invention therefore to produce a street plate in which even though the bearing face should wear paper thin the same will be so braced and supported as to prevent cupping or caving of the same so that the full effectiveness of the plate as a protection 20 to the street or highway is preserved.

A further object is to construct the plate of such material and tensile strength as to materially increase the length of its effective life relative to those now commonly used.

35 A further object of the invention is to produce a simple and inexpensive device and yet one which will be exceedingly effective for the purpose for which it is designed.

These objects I accomplish by means of such 40 structure and relative arrangement of parts as will fully appear by a perusal of the following specification and claim.

In the drawing similar characters of reference 45 indicate corresponding parts in the several views:

Figure 1 is a side elevation of a pair of overlapping track shoes showing my improved street plates thereon, one of said plates being shown in section.

50 Figure 2 is a top plan view of one of the plates.

Figure 3 is a section taken on the line 3—3 of Figure 2.

Referring now more particularly to the characters of reference on the drawing, the numeral 55 1 designates a tractor shoe having the usual grouser 2.

My improved street plate is designated generally as P.

Each plate comprises the bearing face plate 3 which is of course smooth and adapted to ride the street or highway and hold the grouser 2 clear 5 of contact with such street or highway. To this end therefore the face plate 3 is held in spaced relation from the shoe 1 by end walls 4 and an outer side wall 5 which extends from such plate 3 and engages the face of the shoe 1. Flanges 6 10 extend outwardly of the walls 4 and in face to face relation with the shoe 1. These flanges are provided with elongated slots 7 to receive bolts 8 by means of which the plate is bolted to the shoe.

Along one edge of the face plate 3 is an upturned flange 9 which fits over the grouser 2 so that the face plate 3 supports the grouser out 15 of contact with the street or highway.

To support and reinforce the face plate 3 to prevent cupping or caving I provide a rib 10 20 which extends across the inner side of such plate 3 and between the end walls 4 and substantially parallel with the side wall 5. This rib is cut out on a curve as shown quite clearly in Figure 3 to 25 avoid contact with the shoe bolts 1a.

Extending across from the rib 10 to the side wall 5 are a pair of spaced webs 11 while webs 12 extend transversely of the webs 11 to the end walls 4.

Such rib 10 and webs 11 and 12 are of course integrally formed with each other and with the face plate 3. Thus the latter is supported and sustained from all sides against cupping or caving 30 no matter how thin it may become from wear.

The street plate P in its entirety is a forged 35 steel plate made of mild steel. It is annealed under 1800° Fahrenheit for four hours. It has an elongation of 29.5%; a reduction of 44.0%; and a tensile strength of 73600 pounds to the square inch. Thus, in addition to being constructed to avoid cupping or caving when worn thin, the plate is given a maximum wearing capacity.

From the foregoing description it will be readily seen that I have produced such a device as substantially fulfills the objects of the invention as set forth herein.

While this specification sets forth in detail the present and preferred construction of the device, 50 still in practice such deviations from such detail may be resorted to as do not form a departure from the spirit of the invention, as defined by the appended claim.

Having thus described my invention, what I 55

claim as new and useful and desire to secure by Letters Patent is:

An integral street plate for detachable engagement with a tractor track shoe having a transversely extending grouser, comprising a smooth bearing face plate adapted to ride the street surface and hold the grouser of the tractor shoe clear of contact with the street, end walls and a side wall on the face plate and adapted to extend from said plate to the face of the track shoe, flanges extending outwardly from the end walls and adapted to be secured in face to face

contact with the face of the track shoe, an upturned flange along one edge of the face plate adapted to engage the grouser on the track shoe, a rib extending upwardly from the face plate parallel to said flange and spaced a distance ⁵ therefrom to form a groove into which the grouser of the track shoe may be received, reinforcing webs extending between the rib and side wall, and reinforcing ribs extending between the first named webs and the end walls. ¹⁰

GEORGE W. O'CONNOR.
